Primary Examiner — Cynthia Ramirez*(74) Attorney, Agent, or Firm* — Calfee, Halter & Griswold LLP(57) **CLAIM**

The ornamental design for a wheel, as shown and described.

DESCRIPTION

FIG. 1 is a front perspective view of a wheel of the new design;

FIG. 2 is a rear perspective view of a wheel of FIG. 1; FIG. 3 is a top plan view of the wheel of FIG. 1, the bottom plan view being a mirror image thereof;

FIG. 4 is a front elevational view of the wheel of FIG. 1; FIG. 5 is a rear elevational view of the wheel of FIG. 1; FIG. 6 is a left elevational view of the wheel of FIG. 1, the right elevational view being a mirror image thereof;

FIG. 7 is a cross-sectional view of the wheel of FIG. 1 taken along line A-A of FIG. 4; and, FIG. 8 is a magnified front perspective view of a central portion of the wheel of FIG. 1.

The portions of the Figures shown in broken lines are not part of the claimed design and are for illustration only.
